UNITED STATES PATENT OFFICE.

CHRISTIAN MAERTEN, JR., OF NORTH TONAWANDA, NEW YORK;

MECHANICAL MUSICAL INSTRUMENT.

No. 888,830.

Specification of Letters Patent.

Patented May 26, 1908.

Application filed January 29, 1908. Serial No. 413,195.

To all whom it may concern:

Be it known that I, CHRISTIAN MAERTEN, Jr., a citizen of the United States residing at North Tonawanda, in the county of Niagara and State of New York, have invented a new and useful Improvement in Mechanical Musical Instruments, of which the following is a specification.

This invention relates to mechanical or self-playing organs and other musical instruments of the sort in which the pneumatic devices, controlled by a perforated music sheet traveling over the tracker-board and adapted to open and close passages therein leading to the pneumatic devices, automatically operate the instrument. Instruments of this sort are quite commonly used in parks, skating rinks, and other places of amusement where it is desirable to have the instrument render musical selections at predetermined or regular intervals of time, and while instruments have been made which automatically stop at the termination of one or more selections, an attendant is ordinarily required to again start the instrument.

The principal object of this invention is to provide an automatic starting and stopping mechanism for self-playing musical instruments whereby the travel of the music sheet will be arrested and the music stopped at the end of each selection, and the music sheet again started after a period of time has elapsed and the next selection thereon played, when the music sheet contains a plurality of selections, or the selection or selections repeated, without attention of an operative.

Other objects of the invention are to provide an efficient starting and stopping mechanism for this purpose of simple construction which can be applied to the instrument at small expense, and which can be readily adjusted to regulate, as desired, the interval of time between the playing of the selections; also to provide means whereby the music can be started and stopped at will by hand; also to provide in connection with the starting and stopping mechanism, simple means for changing at will the speed of travel of the music sheet to govern the time of the music; and also to improve instruments of this type in the particulars hereinafter described and set forth in the claims. To this end, the music sheet is provided, at the end of the note perforations for each selection thereon,

with a stop perforation which, when it registers with a coöperating passage in the tracker-board, causes the operation of a stop bellows or pneumatic. This pneumatic and the mechanism actuated thereby arrest the music sheet and throw out of action the means which operate the speaking devices, so that the music ceases, and at the same time throw into action a starting gear train which, when it has been in action for a definite period of time, acts through suitable mechanism to again start the music sheet and place the operating means for the speaking devices in action so that the next selection on the music sheet is played. When the music has been thus started, the starting train remains at rest until the end of the selection is reached and the stop pneumatic is again actuated to stop the music, when the starting train will be again set in motion. The music is thus automatically stopped at the end of each selection and again started after a definite lapse of time.

In the accompanying drawings, consisting of three sheets: Figure 1 is a rear elevation, partly in section, of a musical instrument provided with a starting and stopping mechanism embodying the invention, showing the position of the parts when the instrument is not playing. Fig. 2 is a rear sectional elevation of the gearing of the starting and stopping mechanism, showing the position of the parts when a selection is being played. Fig. 3 is a sectional elevation of the starting and stopping mechanism in line 3—3, Fig. 4. Fig. 4 is a sectional plan view thereof in line 4—4, Fig. 3. Fig. 5 is a transverse sectional elevation thereof, on an enlarged scale, in line 5—5, Fig. 1. Fig. 6 is a transverse sectional elevation thereof, on an enlarged scale, in line 6—6, Fig. 1. Fig. 7 is a fragmentary sectional elevation thereof, in line 7—7, Fig. 6, showing a different position of the parts from that shown in Fig. 3.

Like letters of reference refer to like parts in the several figures.

A represents the casing of the instrument, B the main exhaust bellows or reservoir for regulating the vacuum in the vacuum chamber for the various pneumatic motors or pneumatics (not shown) which control the action of the instrument, b the exhaust trunk leading from said vacuum chamber to the reservoir, C C' the pumping bellows

100

105

for exhausting the air from the reservoir B, D the main drive shaft which is driven by any suitable power, and d d' pitmen which connect cranks on the drive shaft to the movable boards of the pumping bellows C C' for operating the same. These parts are common to the ordinary self-playing instrument and may be of any usual or suitable construction and arrangement. In the instrument illustrated, the reservoir and pumping bellows are arranged in the upper part of the casing, and the upper board of the reservoir is stationarily secured in the casing and the lower board thereof is movable, while the lower boards of the pumping bellows C C' are stationarily secured in the casing and the upper boards are movable. This arrangement, however, is not essential. E represents the perforated music sheet which controls the operation of the instrument, and F the tracker-board over which the music sheet travels and which, as usual, is provided with passages with which the perforations of the music sheet register and which are connected by suitable tubes or passages to the various pneumatics of the instrument. As shown, the tracker-board is supported in a suitable frame f mounted on a horizontal shelf or support f' in the casing A. An endless music sheet is preferably employed as thereby the selection or selections contained on the sheet can be played in rotation and repeated as often as desired, by feeding the sheet always in one and the same direction and without necessitating the rewinding thereof. A sheet which has to be rewound could, however, be used without affecting the operation of the instrument until the last selection on the sheet is played, when the sheet could be rewound and the instrument again rewound by hand, or automatically, by mechanism which is well known for this purpose. The music sheet falls in folds in a suitable protecting box f² arranged in the casing below the shelf f' and passes over the tracker-board, ascending and descending through suitable slots f³ f⁴ in the shelf at opposite sides of the tracker-board. The slots are preferably open at the rear edge of the shelf to permit of the music sheet being readily placed in position and removed for changing the sheets, a removable bar f⁵, Fig. 1, being placed in a groove in the edge of the shelf bridging the slots f³ f⁴ for properly supporting the portion of the shelf between the slots. This bar is removed for inserting and removing a sheet. The sheet passes over suitable supporting rollers g g' journaled in the frame f at opposite sides of the tracker-board, and is held down upon said rollers by upper rollers g² g³ removably journaled in the frame f. Small rollers g⁴ are also removably journaled in the frame f and bear

upon the sheet at the opposite edges of the tracker-board to hold the sheet in contact with the board and properly guide it. One of the rollers, for instance, g, is covered with rubber or other suitable material and constitutes the feed roller for the music sheet, 70 while the roller g² above the feed roller is made of metal or is suitably weighted so as to press the music sheet against the feed roller with sufficient force to cause it to be positively fed forward by the rotation of the 75 feed roller. Any other suitable guide and feed arrangement for the sheet could be employed.

The feed roller g is driven by mechanism preferably constructed as follows: H represents a counter-shaft which is journaled in suitable bearings h depending from the shelf f', and is continuously driven from the main drive shaft D by a belt h² passing around pulleys h³ h⁴ on the drive and counter shafts. 80 I represents a shaft movably mounted parallel with the counter-shaft and provided with a wheel i which is adapted to be placed into and out of driving engagement with a wheel i' on the counter-shaft for starting and stopping the music sheet by moving the shaft I toward and from the counter-shaft. The wheels i and i' are preferably, but not necessarily, friction wheels. The wheel i' is preferably a cone wheel and the wheel i is adjustable axially relative thereto for changing the speed of travel of the sheet as hereinafter explained. The movable shaft I is connected with the feed roller g to drive it, by suitable means, such as a chain i² passing 90 around sprocket wheels i³ and i⁴ on the shaft I and the shaft of the feed roller. In the construction shown, the movable shaft I is journaled in the free end of a suitable bearing frame K which is hinged at its other end 105 at k on the shelf f' so that its free end can swing upwardly and downwardly away from and toward the counter-shaft. A suitable spring k' secured at one end of the shelf and bearing at its other end on a cross-bar of the 110 frame K presses downwardly on the frame K, tending to lower the same and hold the friction wheels in driving contact.

The bearing frame K for the movable shaft is connected by any suitable means to the reservoir B so as to be operated by the same. The means shown consists of a lever L fulcrumed between its ends at l in any suitable manner to a stationary part of the instrument, with one end adjustably connected by a link l' to the bearing frame, and the other end bearing against a finger l² projecting from the movable bottom board of the reservoir B. When the bottom board of the reservoir is raised by the suction in the reservoir, which is the normal position thereof when the instrument is playing, the bearing frame K will be lowered by its spring k' and the friction wheels i and

placed in driving engagement, and the music sheet will be fed forwardly.

By opening the reservoir to the atmosphere, the vacuum therein will be destroyed and the bottom board thereof will drop and, through the described connections, raise the bearing frame K and lift the friction wheel i out of driving engagement with its coöperating wheel i' to stop the music sheet. This is 10 accomplished by the following means: The suction trunk b leading to the reservoir B communicates by an opening m with a valve box m', Figs. 1 and 3, which has an opening leading to the atmosphere and controlled by 15 a valve M, hereinafter called the exhaust valve. The exhaust valve shown is hinged to one side of the box and a suitable spring m' tends to close it. The exhaust valve is 20 operated by a stop bellows or pneumatic N through suitable connections. In the instrument illustrated, the stop pneumatic N is mounted on the shelf f' and is connected by tubes n and n' and an interposed box n² to a passage n³, Fig. 3, in the tracker-board. 25 The music sheet is provided with a stop perforation n⁴, Fig. 4, at the end of the note perforations for each piece of music thereon, which is adapted to register with the passage n³ in the tracker-board. Whenever one of 30 these stop perforations n⁴ registers with the tracker-board passage, valves in the valve box n² controlling the stop pneumatic N will be actuated to place said pneumatic in communication with a pipe or passage n⁵ leading 35 from the valve box to the main vacuum chamber or other suction device of the instrument, whereby the stop pneumatic will collapse and through its connections with the exhaust valve M, open the same, as shown in 40 Fig. 1, and stop the music sheet. Valves, such as commonly used for controlling the various pneumatics of self-playing instruments, can be employed for the stop pneumatic. The valve box n², see Fig. 6, is divided 45 into upper and lower chambers by a partition provided with a hole controlled by a valve n⁶ which is connected to and operated by a diaphragm n⁷. The valve n⁶ is connected by an arm to a valve n⁸ controlling a 50 hole in the valve box connecting the upper chamber with the atmosphere. The tube n from the stop pneumatic leads to the upper chamber and the suction pipe n⁵ leads from the lower chamber of the box n², while the 55 tube n' leading to the tracker-board connects by suitable ducts in the valve box with the lower chamber of the box, and a chamber below the diaphragm n⁷. So long as the music sheet closes the tracker-board passage 60 n³, the air will be exhausted from the diaphragm chamber and tracker board tube n', which will hold the diaphragm n⁷ down the valve n⁶ closed and the valve n⁸ open, whereby air can enter the stop pneumatic, which

will remain expanded as shown in Fig. 3. 65 When, however, a stop perforation n⁴ in the music sheet registers with the tracker-board passage n³, air will enter the tube n' and lift the diaphragm n⁷, thereby opening the valve n⁶ and closing the valve n⁸, whereupon the 70 air will be exhausted from the stop pneumatic and the same collapsed.

The means shown for connecting the stop pneumatic N to the exhaust valve M are constructed as follows: o is a link connected at one 75 end to the exhaust valve and adjustably connected at the other end to one arm of a lever o' which is suitably fulcrumed at o² on the shelf f' and has an arm located beneath a lever p pivoted to one side of the casing A. 80 This lever p in turn extends beneath a finger p' projecting from the movable board of the stop pneumatic N, so that when said pneumatic is collapsed, as explained, it will through the levers o' p and link o open the 85 exhaust valve M for stopping the feed of the music sheet. A hand shaft P journaled in a hole in the side of the casing A adjacent to the lever p is provided at its outer end with a suitable handle for turning it, and at its inner 90 end with a cam or arm p² arranged over and adapted to engage said lever p. Thus by turning the hand shaft P the lever p can be depressed and held down independently of the stop pneumatic to open the exhaust 95 valve M for stopping the instrument. By turning the hand shaft P to release the lever p the exhaust valve will be allowed to close under the action of its spring and the suction 100 thereon, thereby again starting the instrument. This arrangement of the connections between the stop pneumatic N and the exhaust valve M is preferable, because the instrument can be stopped and started at will by hand, but any other suitable connections 105 could be employed. As the exhaust valve M controls the exhaust trunk b it will, when opened, destroy the vacuum in the main vacuum chamber and so prevent the sounding of the speaking device in the event that 110 the music sheet is stopped with any of its perforations registering with passages of the tracker-board. The location of the exhaust valve M in the trunk b connecting the reservoir B to the main vacuum chamber is therefore 115 desirable, but manifestly the stop pneumatic could stop the music sheet through other means than the exhaust valve M and reservoir B.

The starting mechanism shown is constructed as follows: Q, Figs. 1 and 7, represents a latch which is suitably pivoted on the shelf f' and has a hook adapted to engage a finger or part q projecting from the movable board of the stop pneumatic N. 125 The latch is pressed toward the projection or finger on the pneumatic by a suitable spring q' and has a beveled end so that when the

pneumatic is collapsed the latch will automatically engage the finger q and hold the movable board of the pneumatic down, as shown in Fig. 1, until the latch is operated to 5 release the pneumatic. R, Figs. 1 and 2, represents a shaft of the starting gear train. This shaft is movably mounted, for instance, in a bearing r pivoted to the shelf f' , and is provided at one end with a worm wheel r' 10 meshing with a worm r^2 on the counter-shaft H and at the other end with the worm r^3 meshing with a worm wheel r^4 secured to a cam shaft r^5 journaled in suitable bearings r^6 . The free end of the bearing for the shaft R is 15 slidably mounted in any suitable manner on the shelf f' and has an extension r^7 arranged to be engaged by an adjustable screw r^8 projecting from the bearing frame K for the movable shaft I of the music sheet feed 20 mechanism. A suitable spring r^9 secured to the shelf f' bears against a projection on said extension r^7 and tends to lift the same and the shaft R. When the bearing frame K is lowered to place the friction wheels i i' 25 in driving engagement, as explained, it will depress the bearing r and shaft R and throw the worm wheel r' out of mesh with the worm r^2 on the counter-shaft so that the starting train will be inactive. When, however, the bearing frame K is lifted to stop 30 the feed of the music sheet as explained, the spring r^9 will lift the bearing r and shaft R and place the worm wheel r' in mesh with the worm r^2 and set the starting train in motion, 35 which will slowly rotate the cam shaft. By using wheels r^4 of different sizes and properly adjusting the shaft R, the speed of the cam shaft can be increased or decreased to give different desired intervals between 40 selections. Any other suitable speed-reducing gearing for driving the cam shaft slowly, and which is thrown into action when the music sheet is stopped and out of action when the music sheet is started, could be employed.

45 A starting cam S, Figs. 3 and 7, is secured to the cam shaft r^5 , and a trip lever s , which is suitably pivoted at s' , is held yieldingly against the cam S by a suitable spring s^2 and is adjustably connected to a trip rod T which 50 is slidably supported in a suitable bearing t with its other end adjacent to the lower end of the latch Q for the stop pneumatic. A spring t' secured to the trip rod and pressing against the bearing t tends to lift the free end 55 of the trip rod T into position to strike the lower end of the latch Q, as shown in Fig. 7, while a wedge or projection t^2 on the trip rod having an inclined face acts, by engagement with the bearing t , to depress the free end of 60 the trip rod out of engagement with the latch Q, as shown in Fig. 1.

When the instrument is playing, the starting train is out of action, the trip lever s rests against the low part of the starting cam

S, and the trip rod is out of engagement with the latch Q, as shown in Fig. 1, so that the latch is free to engage and hold the stop pneumatic when collapsed by the registration of a stop perforation n^4 of the music sheet with the coöperating passage of the 65 tracker-board, as before explained. When the music sheet is stopped and the starting train set in motion, the starting cam S will slowly revolve in the direction indicated by the arrow in Fig. 7 and retract the trip lever 70 s and trip rod T. When the wedge t^2 on the trip rod clears the bearing t , the spring t' will lift the free end of the trip rod to a position opposite to the lower end of the latch Q. When the high part of the cam clears the 75 part of the trip lever bearing thereon, the spring s^2 will pull the trip lever and trip rod forwardly and the latter will swing the latch Q to release the stop pneumatic. Before the trip rod reaches the limit of its advance movement the wedge t^2 will depress its free end out of engagement with the end of the latch Q, thus leaving the latch free to engage and hold the stop pneumatic when it is again collapsed.

80 The movable friction wheel i of the music sheet driving mechanism is preferably adjustable, by any suitable means, axially on its shaft I so that it can be moved to bear on a larger or smaller part of the wheel i' to 85 change the speed of the music sheet. In the construction shown, the shaft I is square in cross-section and the wheel i is shifted thereon by a lever U which is pivoted on the bearing frame K for said shaft and is connected 90 by a link u and fork u' to the grooved hub of the wheel i . The speed of the music sheet can be readily changed as desired at any time, by a proper adjustment of the shift lever U. The counter-shaft H carrying the 95 cone wheel is preferably arranged at an angle to the shaft I so that the top face of the cone wheel will be parallel with the shaft I and thus enable the wheels i i' to be engaged and disengaged by like vertical movements of the 100 frame K regardless of the adjustment of the wheel i on its shaft I.

105 While the starting and stopping mechanism is primarily intended for application to pneumatically operated instruments, and pneumatic means are described for stopping the music sheet, it will be manifest that mechanism similar in its general organization and mode of operation could be applied to other types of musical instruments and 110 controlled by the moving member which controls the playing of the instrument.

115 I claim as my invention:

1. In a musical instrument, the combination with the traveling member which controls the operation of the instrument, of means also controlled by said traveling member for stopping the same at the end of a selection,

- and a time-starting mechanism which is set in motion by the actuation of said stopping means and automatically starts said traveling member again after a lapse of time, substantially as set forth.
2. In a musical instrument, the combination with the traveling music sheet which controls the operation of the instrument, of means also controlled by said music sheet for stopping the feed of the music sheet at the end of a selection, and a time starting mechanism which is set in motion by the actuation of said stopping means and automatically starts said music sheet again after a lapse of time, substantially as set forth.
3. In a musical instrument, the combination with the traveling music sheet which controls the operation of the instrument, of a pneumatic also controlled by said music sheet, means controlled by said pneumatic for stopping the feed of said music sheet, a time starting mechanism which is set in motion by said stopping means when actuated, and a releasing device for said pneumatic which is actuated by said starting mechanism after a lapse of time, substantially as set forth.
4. In a musical instrument, the combination with the music sheet which controls the operation of the instrument, of feed mechanism for said music sheet, pneumatic means for starting and stopping said feed mechanism, a stop pneumatic which is controlled by said music sheet and controls said feed mechanism, time starting mechanism which is set in motion by said pneumatic means when actuated to stop the feed of the music sheet, and a latch device which holds said stop pneumatic inactive and is actuated by said starting mechanism after a lapse of time to release said pneumatic, substantially as set forth.
5. In a musical instrument, the combination with the music sheet which controls the operation of the instrument, of feed means for said music sheet, a suction bellows and connections for stopping and starting said sheet feed means, a valve controlling said bellows, means controlled by said music sheet for operating said valve to stop the music sheet, and a time starting mechanism which is set in motion by said connections and automatically controls said valve operating means to cause said bellows to start the music sheet after a lapse of time, substantially as set forth.
6. In a musical instrument, the combination of a music sheet, means for feeding the same, pneumatic means which are controlled by said music sheet and which in turn control said feed means and the speaking devices of the instrument, and a time starting mechanism which is set in motion by said pneumatic means and controls said pneumatic means for automatically starting the music sheet and rendering the speaking devices active after a lapse of time, substantially as set forth.
7. In a musical instrument, the combination of a music sheet which controls the operation of the instrument, feed mechanism therefor, a bellows and connections or the like for stopping and starting said feed mechanism, means including a pneumatic which are controlled by said music sheet and control the operation of said bellows, a latch for holding said pneumatic when operated to stop the sheet feed mechanism, and a time starting mechanism which is set in motion by said bellows connections when said feed mechanism is stopped and which automatically actuates said latch to release said pneumatic after a lapse of time, substantially as set forth.
8. In a musical instrument, the combination of a music sheet which controls the operation of the instrument, feed mechanism therefor comprising a gear which is movable into and out of driving engagement with a coöperating gear to start and stop the music sheet, a bellows or the like and connections which control the position of said movable gear, means including a pneumatic which are controlled by said music sheet and control said bellows, a latch for holding said pneumatic when operated to stop the music sheet, a starting device for actuating said latch to release said pneumatic, and a time mechanism for operating said starting device, comprising coöperating gears one of which is moved into driving engagement with the other by said bellows connections when the music sheet is stopped, substantially as set forth.
9. In a musical instrument, the combination with the music sheet which controls the operation of the instrument, of feed mechanism for said music sheet, means controlled by said music sheet for stopping said feed mechanism at the end of a selection, and a time starting mechanism which is set in motion by said stopping means and automatically starts said feed mechanism after a lapse of time, said feed mechanism including means for regulating the speed of the music sheet, substantially as set forth.
10. In a musical instrument, the combination with the traveling member which controls the operation of the instrument, of means also controlled by said traveling member for stopping the same at the end of a selection, a time starting mechanism which is set in motion by the actuation of said stopping means and automatically starts said traveling member again after a lapse of time, and manually operated means for stopping and starting said traveling member at will, substantially as set forth.

11. In a musical instrument, the combination with the traveling music sheet which controls the operation of the instrument, of means also controlled by said music sheet for stopping the feed of the music sheet at the end of a selection, a time starting mechanism which is set in motion by the actuation of said stopping means and automatically starts said music sheet again after a lapse of

time, and manually operated means for stopping and starting said music sheet as will, substantially as set forth.

Witness my hand, this 22d day of January, 1908.

CHRISTIAN MAERTEN, JR.
